CLAIM

The ornamental design for a connector hub, as shown and described.

DESCRIPTION

FIG. 1 is a left, front and top perspective view of a connector hub, showing our new design;

FIG. 2 is a right, back and bottom perspective view of the connector hub of FIG. 1;

FIG. 3 is a right side view of the connector hub of FIG. 1;

FIG. 4 is a top view of the connector hub of FIG. 1;

FIG. 5 is a left side view of the connector hub of FIG. 1;

FIG. 6 is a bottom view of the connector hub of FIG. 1;

FIG. 7 is a back view of the connector hub of FIG. 1; and,

FIG. 8 is a front view of the connector hub of FIG. 1.

The broken lines immediately adjacent the shaded areas represent the bounds of the claimed design while all other broken lines are directed to environment and are for illustrative purposes only; the broken lines form no part of the claimed design.
